US0D1034433S

(12) **United States Design Patent** (10) **Patent No.:** **US D1,034,433 S**
(45) **Date of Patent:** **** Jul. 9, 2024**

(54) **MOBILE POWER**

(71) Applicant: **Shenzhen Utopia—Originality Technology Co., Ltd**, Shenzhen (CN)

(72) Inventor: **Hongyuan Lu**, Shenzhen (CN)

(73) Assignee: **Shenzhen Utopia-Originality Technology Co., Ltd**, Shenzhen (CN)

(**) Term: **15 Years**

(21) Appl. No.: **29/848,410**

(22) Filed: **Aug. 2, 2022**

(51) **LOC (14) Cl.** **13-02**

(52) **U.S. Cl.**

USPC **D13/103**

(58) **Field of Classification Search**

USPC ..... D13/103—106, 110, 118, 119, 184, 199; D14/253, 432, 434

CPC H02J 50/05; H02J 7/0049; H02J 7/0047

See application file for complete search history.

(57) **CLAIM**

The ornamental design for a mobile power, as shown and described.

DESCRIPTION

FIG. 1 is a perspective view of a mobile power, showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

1 Claim, 8 Drawing Sheets
